DRILL

Victor S. Karbowski, Lima, Peru

Application March 18, 1949, Serial No. 82,165

In Canada January 8, 1949

4 Claims. (Cl. 255—76)

1

This invention relates to drills suitable for drilling rock and is herein described in some detail as embodied in an expansion drill, adapted to produce a blast hole with an enlarged, bottle-like or ball-like chamber at the inner end of the blast hole. Such a chamber may hold a much greater charge of blasting charge than the usual cylindrical drilled opening.

Not only does such a chamber hold more explosive than the usual cylindrical drill hole, but the relatively narrow opening of the chamber serves as a partial tamping or plugging over the explosive in the hole.

As a result, the charge, when exploding, is more concentrated, is deeper in the rock, and may be caused to break the rock in larger lumps with less charge of explosive.

Thus, the expansion drill enables blasting to be done with less explosive and with less depth of drill hole. In this way, drilling time is saved, as well as man-hours.

Another advantage is the reduction in amount of the detrimental silicosis powder produced in drilling for each charge of explosive.

The drilling device may take any one of several forms, but in each form is free from the objectionable weaknesses of prior devices intended to serve as expansion drills, but which relied on pivots that failed to withstand the strains and shocks incidental to drilling.

In the device of the present invention, the preferred form provides a V-shaped track or seat as a circular arc in which the V-shaped face of the back of the cutting element seats itself to provide a large area to carry the blows of the drill on the rock, and the large pivot receives only part of any such blow. Thus a highly rugged device is provided.

Other features and advantages will herein-after appear.

In the accompanying drawings:

Fig. 1 shows a side view of one form of cutting end of its drill.

Fig. 2 is a side view, broken away to show the internal structure.

Fig. 3 is a view of an alternative form with screwed on removable head.

Fig. 4 is a front view of the same.

Fig. 5 is a face view of one form of the pivoted cutters.

Fig. 6 is an edge view of the same.

Fig. 7 shows a fourth form in side view.

Fig. 8 is an end view of the parts in Fig. 7.

Fig. 9 is an end view of still another form.

Fig. 10 is a side view of a modification.

Fig. 11 is a front view of the same largely in section.

Each drill cutting edge point 20 of Fig. 1 is shown as the intersection of tangents drawn at 60° or a little more from an integral cutter blade or body 21 having a circular arc back 22.

The circular arc back is shown as V-shaped

and as lying in a V-shaped circular arc 23 forming a track in the drill end 24, so that the body 21 may rotate over a considerable angle in track 23 and face it over a large area.

The drill shank or end 24 in Fig. 1 carries in a transverse hole 25 or bore a heavy bolt 26 which passes through center holes 27 in the two bodies 21 and serves as a shaft on which the bodies 21 may turn, but fits closely enough to keep the V-shaped backs 22 well seated in the V-shaped tracks 23.

The bolt 26 includes a rounded head 31 lying outside of one body 21, but lying wholly within the imaginary outside prolongation of the shank 24, and the other end of the bolt 26 also terminates within the imaginary prolongation of the shank 24 and is pierced outside the other body 21 by a transverse hole to receive a headed split pin 28, so the pin 28 may have its end split open to bear against the outside of the other body 21 and securely hold the bolt 26 and both bodies 21 assembled.

Each body 21 is tapered to cause the cutting edge 20 to form an angle of about 60° and is shown as about one-fifth of the thickness of the enlarged shank 24.

The taper or V-shape of the cutting edge extends wholly around the periphery of the body and the track 23 is out to face and fit the tapered edge 20, so that the body 21 seats itself in the track 23 at any angle at which the body 21 stands and thus receives the shocks of drilling over a large area.

The throw of the cutting edge transversely of the axis of the drill to cutting position is limited by the end 32 of the track 23 which ends so that a straight tangential edge 29 can turn no further when the other tangential edge 30 of the body 21 stands approximately directly across the opening drilled on the rock, as indicated in dotted lines in Fig. 1.

Thus the opened edges 20 drill a hole of maximum possible reach of the edges 20 on the two bodies 21, or nearly double the diameter of the hole drilled by the circular boundary diameter of the bodies 21.

As appears in Fig. 1, the hole 25 furnishes a bearing about twice the thickness of a body 21 in length and so gives considerable bearing support for the shaft or bolt 26.

The bolt 26 is shown of a diameter about equal to its length between bodies 21 and about one-third the total circular diameter of a body 21.

As appears in Figs. 1 and 2, the ends 32 of the tracks 23 are cut away at an angle, so that whole taper surface of each cutting edge 20 begins to lie on the track 23 at about the same time, distributing the load uniformly on the taper surface of the body 21.

In order to make sure that bodies or cutting blades 21 swing outwardly rather than inwardly, each is provided with an inwardly facing lug 34 (dotted lines in Fig. 1) or offset adapted to

lie against a cooperating step or lug 29 on the flat face of drill end 36, when a cutting blade lies so as to cut directly axially of the drill body. The end 35 is shown as rounded at its tip.

The cutting blade 21 can, however, swing freely to carry its point 20 beyond the body of the drill on the opposite side.

The lug 34 lies, preferably, on the inner face of its cutting blade 21, where it is least exposed to damage, and lies on a portion of the edge that normally is clear of the rock in drilling.

Thus when the drill body is lifted out of the drilled hole the points 20 of the cutting bodies swing in on their shaft and allow the drill to be withdrawn from the larger chamber into the smaller cylindrical drill hole.

The alternative form of drill head shown in Figs. 3 and 4, provides a screwed-on head 37, the screw being shown at 38, where the enlarged head unites with the shank 24.

In the form shown in Figs. 3 and 4, the cutting blades 39 and 40 lie against each other between two ears 41, 42 which project beyond the head 37 and carry a heavy shaft bolt 43 with slotted head 44 on one end and split pin 45, both lying outside the ears 41, 42. But the whole bolt 43 lies within an imaginary prolongation of the head 37 and the two cutting edges 39, 40 may be held to lie within that prolongation.

In the form shown more in detail in Figs. 5 and 6, each cutting blade 39 and 40 is shaped in outline like a cutter blade of Fig. 1, but carries on its outer face a pin or lug 46 adapted to lie against a pin 46a welded on the arcuate periphery of each ear 41, 42 when the points 20, 20 point forward. Thus, neither blade can ever swing inwardly beyond center, but is free to fall into the full line, Fig. 3, position.

In the form of drill head shown in Fig. 7, two cutting edges 47, 48 are separately mounted in spaced parallel pivot cross shafts 49, 50, which may take the form of headed bolts 51, 52, held against slipping out by split pins 53, 54.

The cutting edges 47, 48 may take the form of smaller bodies but otherwise much like the bodies 21 of Fig. 1, though mounted between extension ears 55 (see Fig. 8), projecting from the drill body 24. Preferably, the cutting edges 47, 48 can turn only as far as to bring their tangential edges 56 parallel to but below the bottoms of the ears 55. It is impossible for any edge to swing so its point 47 or 48 swings inwardly, since the other edge blocks it.

A four-edge drill head is shown in Fig. 9, in which four L-shaped ears 59 project from the drill shaft axially, with transverse headed pivot bolts 60 passing through adjacent arms of the L's. Each of the four pivots 60 may carry a cutting edge member 61, so that their points, when swung out, as shown in dotted lines in Fig. 7, cut an enlarged bore, and when swung in lie on or within the circle around the ears 59, as do the outer edges of the cutting edge members 47, 48 of Fig. 7 on the circle of the ears 55 in that figure.

In the form shown in Figs. 10 and 11, the cutters 39 and 40 of Figs. 3 and 4, turn on a bolt 62 having a depression 63 in one head 64, shown as expanded as a rivet head in the countersunk end 65 of the bolt opening through the ears 41 and 42. The head 64 is easily drilled out and the bolt 62 removed. The cutters 39 and 40 each carry a pin 46 which lies against the squared end 66 of a lug 67 on the curved periphery of the adjacent ear 41 or 42 when the cutter point points

forward. The lug 67, therefore, prevents the cutter from turning beyond dead center.

Figs. 10 and 11 also show a removable seat 68 lying between the ears 41, 42 and resting its flat back 69 on the bottom 70 of a channel 71 between said ears. The seat 68 is provided with triangular arcuate channels 72 in which the nearly circular backs 22 of the cutters 39 and 40 seat themselves snugly. The seat 68 is shown as including a nearly square shallow projection 73 on its back which fits into a corresponding hollow 74 in the end of the body 24, thus holding the seat 68 centered.

While the backs 22 of the cutters 39 and 40 of Figs. 10 and 11 are described above as nearly circular, their arcs end in long tangents 76, and the supporting channels in the seat 68 are shown as carried straight outwardly in an extension of the seat 68 reaching the maximum diameter of the drill head 37 in these figures.

The cutters 39 and 40 of Figs. 10 and 11, are shown with convex cutting edges 76, and these seem to be advantageous in cutting relatively soft rock such as shale.

Moreover, after a drill hole has been enlarged at its bottom by the cutters of Fig. 1 or 3, it may be further enlarged as it is further advanced by the cutters of Fig. 10, thus making shoulders above the charge of explosive on the end of the drill hole.

The drillbody 24, the drill head 37, and the shallow projection 73, are shown with central small longitudinal hollow bore 75, extending down to the channel.

Having thus described certain forms of the invention in some detail, what is claimed is:

1. An impact drill including a shank, a pivot passing through the shank transversely of its length, circular arc faces on the shank struck from the pivot center and forming V tracks, flat disc cutter blade members each having a circular arc V-shaped bearing back portion adapted to fit and slide on a V track, and a V-shaped cutting portion formed by portions of the blade extending on a tangent from the V-shaped circular arc bearing portion and meeting at a point, so that the V-shaped edge extends completely around the blade.

2. A device according to claim 1 in which the blades each carry a lug adapted to hold its blade arrested against turning backward beyond its center.

3. A device according to claim 1 in which the shank is formed with a projecting lug through which the pivot passes and which lies between the cutter blades.

4. A device according to claim 1 in which the blades lie against each other and the pivot passes through the blades and through a projecting lug of the shank outside each blade.
